Primary Examiner — Bao-Yen T Nguyen*Assistant Examiner* — Emily Anna Saunders**CLAIM**

The ornamental design for a fidget ball, as shown and described.

DESCRIPTION

FIG. 1 is a top perspective view of a fidget ball, showing my new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a bottom perspective view thereof, in a partially open configuration; and,

FIG. 10 is a top perspective view thereof, in an open configuration.

The broken lines in the drawings depict portions of the fidget ball that form no part of the claimed design.
